WALL JACK

Marvin W. Coleman, Dearborn, Mich.

Application March 26, 1956, Serial No. 573,746

1 Claim. (Cl. 214—1)

This invention relates to hoisting apparatus and more particularly to a wall jack.

The practice of fabricating walls in a horizontal position, and then raising them, is firmly established in the building trades as a time and money saver as well as a safer method of operation since no scaffold work is involved. One object of this invention is to provide a device for raising a wall or the like which has been fabricated in horizontal position.

Another object of the invention is to provide a wall jack comprising a base, a gyn pole pivoted to the base and a lifting member attachable to the wall with means such as a winch and cable associated with the gyn pole and connected to the lifting member for moving the latter along the length of the gyn pole to raise the wall or the like attached to the lifting member.

A further object of the invention is to provide a gyn pole having stop means at intervals along the length thereof for preventing back travel of the lifting member. Thus, if for any reason, such as a break in cable, the lifting member should move down suddenly relative to the gyn pole, the stop means will positively break the downward movement of the lifting member.

Still another object of the invention is to provide a wall jack having provision for preventing the lifting member from becoming separated from the gyn pole. In the event of a cable break, for example, the downward movement of the lifting member takes place with such force and suddenness that it tends to push or throw the gyn pole back away from the wall. It is essential that the lifting member and gyn pole do not become separated since in that event the lifting member will bypass the stop means on the gyn pole and the wall or the like attached thereto would come crashing down.

Still another object of the invention is to provide means facilitating the movement of the lifting member along the gyn pole.

A still further object of the invention is to provide means for preventing the relative movement of the lifting member away from the gyn pole in a direction transversely of the path of swinging movement of the gyn pole.

Other objects of the invention will become apparent as the following description proceeds, especially when considered in connection with the accompanying drawings, wherein:

Figure 1 is a perspective view showing two wall jacks embodying the present invention, the wall jacks being shown lifting a wall into raised position.

Figure 2 is a perspective view of a wall jack.

Figure 3 is a sectional view taken along the line 3—3 on Figure 2.

Figure 4 is an elevational view of the upper end portion of the wall jack.

Figure 5 is a sectional view taken along the line 5—5 on Figure 2.

Figure 6 is a view taken along the line 6—6 on Figure 5.

2

Referring now more particularly to the drawings, a pair of identical wall jacks, generally indicated at 10, are shown in Figure 1 in the act of raising a wall W from horizontal position to upright position. Each wall jack 10 comprises a base 12 and a gyn pole or boom 14. The base comprises a pair of laterally spaced angle members 16 which extend parallel to one another and which are connected by a cylindrical shaft 18 having its opposite ends extending through the upright flanges of the angle members and rigidly secured thereto. The coplanar horizontal flanges 20 of each angle member are formed with a plurality of openings so that the base may be secured to a supporting surface by nailing.

The gyn pole or boom 14 comprises an elongated channel member 22. An attaching frame 24 is rigidly secured to the boom adjacent the lower end thereof. Specifically, the frame includes a pair of legs 26 which extend from the connecting portion 28 of the frame in diverging relation toward the lower end of the channel member 22. The connecting portion is secured directly to the base 30 of the channel member 22 by suitable fastening elements.

An open-ended tube 32 extends between and is secured to the free ends of the legs 26, and the tube loosely receives shaft 18 to permit rotation of the tube and, hence, the entire boom 14 about the axis of the shaft 18. When, as usually happens, the base is supported on a horizontal surface, the shaft 18 is also horizontal and the boom or gyn pole swings in a vertical plane. The lower end of the channel member 22 may have its base welded directly to the tube 32 if desired.

The cable anchor or lifting member is indicated generally at 34 and comprises an angle member 36 adapted for direct attachment to a portion of a wall or the like to be lifted. One of the flanges 37 of the angle member 36 is provided with a plurality of openings to permit the lifting member to be attached to the wall by nailing. A pair of plates 38 are secured to the apertured flange of angle member 36 in laterally spaced parallel relation. A shaft 40 extends through and is secured rigidly to plates 38 with rollers 42 respectively journaled for rotation on the opposite ends of the shaft. These rollers are adapted to have a rolling engagement with the base 30 of the channel member 22. The channel member 22 has side flanges 44 which are parallel and extend at right angles to the base 30, and the rollers are respectively disposed closely adjacent to the side flanges 44 to practically eliminate any movement of the lifting member transversely of the path of swinging movement of the boom.

It will be noted that a pair of flanges 46 extend laterally inwardly from the free edges of the flanges 44. The flanges 46 extend parallel to the base of the channel member and in the same plane, overlying the rollers to prevent the lifting member from becoming separated from the channel member 22 during the lifting operation. This relationship can best be seen in Figures 5 and 6.

Means including a cable 48 are provided for raising the lifting member 34 relative to the boom. The cable 48 has one end secured to a pin 50 connecting the plates 38 and is trained over a pulley 52 beyond the upper end of the channel member 22. Specifically, the pulley 52 is journaled on a stub shaft 54 extending between the angle members 56 which are rigidly secured in parallel relation to the base 30 of the channel member at the outer side thereof. The other end of the cable is operated by a winch indicated at 58. The winch includes a reel 60 about which the cable is wound, and a crank 62 for rotating the reel 60 through suitable gearing (not shown). A dog 63 is provided cooperable with the gearing to permit the reel to be wound only in a direction to

take up the cable. The reel may be wound in the opposite direction only by manually retracting the dog 63.

The channel member 22 is provided with means for preventing back travel of the lifting member. Such means includes a plurality of stop members 70 located at closely spaced intervals along the length of the boom. These stop members are preferably spaced about six inches apart. The stop members are rigidly secured to the base of the channel member at the inner side thereof and have upwardly inclined cam surfaces 72 which merge into the rounded head portions 74. The stop members are adapted for cooperating with the pivoted dog 76. Dog 76 has its upper end pivoted on a pin 78 secured to and extending between plates 38. The dog is in the form of an angle plate, and the bottom surface of the free end portion thereof has a concave recess 80 adapted to receive head portion 74 of the stop members. The transverse surface 82 at the free end of the dog is inclined at approximately the same angle as the cam surface 72 to enable the dog to cam past the stop members during its upward travel. However, when the lifting member moves downwardly relative to the channel member 22, the head portion 74 of a stop member extends into the concave recess 82 to prevent further downward movement of the lifting member.

A pin 84 is rigidly secured to and extends between shaft 40 and the apertured flange 37 of angle member 36. The dog 76 has an opening for loosely receiving the pin and a compression coil spring 86 encircles the pin and has its opposite ends abutting the angle member 36 and the dog 76. As a result, the spring 86 normally holds the dog in the position shown in Figure 5, the dog, however, being able to cam past the stop members against the action of the spring during upward movement.

It will be noted in Figure 2 that the flanges 46 terminate short of the lower end of the channel member 22. This is to permit the rollers 42 of the lifting member to be inserted within the channel at the beginning of the lifting operation.

In operation, the lifting member is separated from the channel member and the attaching angle member 36 thereof is secured to the wall to be lifted by any suitable means such as by nailing. The wall will be lying flat on a supporting surface with side W' down and it is a simple matter to lift the wall slightly with a wedge or hammer claw to insert flange 100 of angle member 36 under the wall. The flange 37 is attached by nailing. The base of the device is then positioned close to the lifting member so that the rollers 42 thereof may be inserted into the channel member at the lower end. The base is then nailed to the floor, and by operation of the winch, the lifting member will be raised along the length of the boom. Usually, as in Figure 1, the floor is horizontal so the boom swings in a vertical plane about the horizontal axis of shaft 18 during the lifting operation. As the wall is raised, the dog 76 will cam past the successive stop members 70. However, if for any reason the lifting member should suddenly move down with respect to the boom as, for example, if the cable should break, the dog will cooperate with the stop member located immediately therebeneath to prevent further downward movement of the lifting member and thereby prevent the wall from crashing down on the supporting surface.

The lifting member is closely held within the confines of the channel member so that the dog will not be moved out of operative relationship with the stop stations during the lifting operation. Also, the rollers 42

provide a near frictionless movement of the lifting member.

What I claim as my invention is:

A jack comprising a base, an elongated boom members, means pivotally mounting one end of said boom member to said base for swinging movement in a generally vertical plane, a lifting member attachable to a building wall or the like and supported on said boom member for movement along the length thereof, said members being provided with cooperating engaging means for guiding the movement of said lifting member lengthwise along said boom member and positively preventing lateral separation of said lifting member from said boom member, means for moving said lifting member along the length of said boom member in a direction away from said one end thereof to raise a building wall or the like attached thereto, and means independent of said moving means for preventing movement of said lifting member along the length of said boom member in the opposite direction, said lifting member and said last mentioned means comprising a plurality of stops permanently mounted on said boom member, a pair of spaced apart right triangular plates having a vertical and a horizontal leg and also having the acute corners thereof removed, said plates being held parallel to each other in spaced relation by an angle shaped member which is adapted to be moved parallel to said boom member, the back of one leg of said angle member being rigidly attached to the vertical leg of said plates, the horizontal leg of said plates extending from said angle member toward said boom member, the other leg of said angle member extending outwardly from the boom member, three axle members extending between said plates along the hypotenuse thereof, including an upper axle member to which said moving means is attached, a lower axle member having anti-friction rollers attached to the ends thereof which are engageable with said boom member, and a middle axle member having a second angle member which is in back to back relationship with said first mentioned angle member pivotally mounted thereon, said pivot being at the tip of the vertical leg of said second angle member, the horizontal leg of said second angle member being below said lower axle member and extending substantially to said boom member, a dowel member extending between the first mentioned angle member and the lower lower axle member through said second angle member and carrying a spring mounted between the two angle members, whereby said pivotally mounted second angle member is pressed against said lower axle member causing said second angle member to cam past said stops when the lifting member is moved in one direction, said stops and second angle member acting together to prevent movement of said lifting member in the opposite direction.
